UNITED STATES PATENT OFFICE

154,774

DESIGN FOR AN INFLATABLE BOAT

Herschel G. Harris, New York, and Franklyn S. Weisgerber, Fishkill, N. Y., assignors to New York Rubber Corporation, New York, N. Y., a corporation of New York

Application August 5, 1947, Serial No. 140,702

Term of patent 14 years

(Cl. D71—1)

To all whom it may concern:

Be it known that we, Herschel G. Harris and Franklyn S. Weisgerber, citizens of the United States and residents, respectively, of the Borough of Manhattan, in the city, county, and State of New York; and of Fishkill, in the county of Dutchess and State of New York, have invented a new, original, and ornamental Design for an Inflatable Boat, reference being had to the accompanying drawing, forming a part thereof.

Fig. 1 represents a top plan view of an inflatable boat, embodying our new design;

Fig. 2 represents a side elevation thereof;

Fig. 3 represents a rear elevation thereof;

Fig. 4 represents a front elevation thereof; and

Fig. 5 represents a transverse section taken in the plane of the line V—V of Fig. 1, looking in the direction of the arrows.

The dominant features of our design reside in the portions shown in full lines.

We claim:

The ornamental design for an inflatable boat, substantially as shown and described.

HERSCHEL G. HARRIS.

FRANKLYN S. WEISGERBER.
